SHIRT CONSTRUCTION

William Meisler, Union City, and Milton Wolf,
Jersey City, N. J.

Application March 11, 1935, Serial No. 10,508

2 Claims. (Cl. 2—123)

This invention relates to improvements in shirts and more particularly to the construction of the cuffs thereof, whereby a more economical system of manufacturing may be obtained 5 and whereby it becomes possible to effect large economies in the retail distribution of the shirts. While the following discussion and detailed description of the invention will be made with reference to an outer or dress shirt, e. g. a man's 10 shirt, it is to be understood that the invention may be applied with profit to the construction of any type of garment provided with sleeves.

Ready-to-wear shirts are usually sold according to size of collar or neckband and according 15 to sleeve length. Considering the case of men's shirts, the shirts come in sizes of 14 to 17 for the neckband, or collar, increasing by half sizes. Thus the manufacturer will usually make and the retailer will be stocked with the following series 20 of sizes, namely 14, 14½, 15, 15½, 16, 16½ and 17, altogether seven distinct sizes. A shirt having one of these neckband or collar sizes is manufactured in varying sleeve lengths. Taking the case of white shirts, the manufacturer usually 25 provides sleeve lengths varying from 31 to 37 inches inclusive, increasing by one inch; hence, in seven distinct lengths. The retailer is therefore confronted with the necessity of carrying each of the collar sizes in all of these multiple 30 sleeve lengths and as a result must stock no less than forty-nine different lots and, it must be remembered, that so far the discussion has been with reference to white shirts only. It will be readily appreciated what a problem these various 35 sleeve lengths now present to the manufacturer and still more so, to the average, comparatively small, shirt retailer. In order that he may be in a position to satisfy the demands of any customer, for ready-to-wear shirts, he 40 must keep continually in stock a large number of sizes many of which are only in demand at infrequent intervals. If he does not keep all the sizes in stock, he runs the risk of losing a sale and very often, a customer.

If one takes into consideration, the present 45 popular demand for colored, or "novelty" ready-to-wear shirts, the seriousness of the problem as outlined above will be readily understood.

Many attempts have been made to solve the 50 problem. Thus it has heretofore been proposed to provide the sleeve with a series of fastener members and a single cooperating fastener member on the body portion of the shirt, whereby the length of the sleeve may be adjusted. It has 55 also been proposed to provide the cuff of the

sleeve with a series of concealed pleats or lines of stitches, which may be successively removed in order to obtain the desired sleeve length. In a different manufacturing line, that of "sweat" shirts it has been proposed to provide the sleeves with relatively elastic, knitted panels, extending throughout the whole length of the sleeve, the knitted structure including a continuous cuff, the latter being of course distinguished from the split cuff of the usual outer shirt. While this 10 structure has been primarily designed to permit ready removal of the garment, it has the incidental advantage that it permits minor accommodations of size variations. However, the latter types of garments are not to be confused 15 with the highly specialized class of outer or dress shirts (1) where particular problems of manufacture and distribution have to be considered; (2) where the requirement of the customary split cuff structure has to be accommodated, and (3) in particular, where the paramount necessity of neat appearance demanded by the user has to be satisfied. As far as is known, none of the proposals has attained any practical importance in the actual manufacture 20 of shirts.

In addition to these heretofore proposed expedients, it is of course, well known to use at times separate elastic bands, which are placed on the forearms over the shirt sleeves.

These several expedients, while useful, present the objections of being uncomfortable or, in some cases, actually injurious to the health of the wearer, as in the case of the separate or garter type of armband. Moreover, in practically every instance the sleeve has to undergo some alteration or modification concomitant with a sale which, even in the case of a simple or outer ready-to-wear shirt occasions delay and/or some expense. While these objections 40 may appear to be relatively slight, the shirt manufacturers and particularly the shirt retailers, have for years endeavored to remedy the condition recited as, in most cases, it prevents the shirt from being immediately used upon its 45 sale, and hence causes considerable inconvenience to the customer.

Briefly stated, the present invention overcomes the disagreeable and unsightly effects of oversized sleeves and at the same time, eliminates the 50 necessity for the manufacturer to make and the retailer to stock, in the case of ready-to-wear outer shirts, a permutation of neckband sizes, or collar sizes, and sleeve lengths. The disadvantages of the current system of manufacture and 55

retail distribution are considerably minimized by the present invention and result in a substantial economy to the purchaser. Moreover, the product as sold over the counter requires no alteration or modification whatsoever, the invention being embodied as a permanent part of the cuff structure, rendering the sleeve adjustable within satisfactory practical limits and making the shirt in which the invention is incorporated available for immediate use. The invention does not impair the durability and appearance of the shirt or discomfort or injure the wearer in the least, and a shirt constructed according to the invention may be made by simple manufacturing methods.

Referring to the drawing:

Figure 1 is a perspective view of the lower portion of a sleeve and showing the invention applied to the cuff of the sleeve, which is associated with the conventional outer ready-to-wear shirt (not shown).

Figure 2 is a view in elevation showing the split cuff of Figure 1 fully extended.

Figure 3 is a diagram indicating the series of sleeve lengths which heretofore have been associated with each one of the series of neckband sizes, e. g. in case of white shirts.

In Figure 1 there is illustrated the lower portion of a sleeve 10 which is customarily attached to the conventional outer or dress, ready-to-wear shirt (not shown) and in position upon the arm of the wearer. This sleeve includes a cuff portion 11 of the split type, the opposed edges of which are indicated by the reference numerals 12 and 13. The cuff 11 is provided with one of the usual types of separable fastener means, e. g. a button 14 and corresponding buttonhole 15.

By reference to Figure 2 it will be seen that the cuff 11 is provided within its confines and/or as an integral part thereof with a coplanar elastic means represented by the numeral 16. This elastic means may be of any desired structure or material, of which many varieties are commercially available, and which will exert its elasticity transversely of the sleeve, i. e. in the direction of the arrows shown in Figure 2. In the practical embodiment of this invention, it was found that the material known as "Lastex" is very satisfactory in this connection, since it can be (1) knitted and (2) prepared as a white material or suitably colored, so as to be indistinguishable from the remainder of the cuff and shirt material, (3) will absorb perspiration and (4) is washable. As illustrated in the drawing, this elastic means is embodied in the form of a trapezoidal shaped panel or insert secured to the bottom of the sleeve 10 and the adjacent side portions of the cuff 17, 18 by suitable lines of stitching 19, 20. The length of the larger or major base portion of the panel 16 varies in accordance with the size of the neckband of the shirt with which the cuff is associated. As will be readily appreciated these lines of stitching are of a type to present a smooth, continuous and uninterrupted appearance to the cuff. In connection with the line of stitching 19 it is preferred to have this relatively loose, in order to compensate for the strains incidental to stretching and, in this connection, the adjacent sleeve portion is provided with gatherings or pleats 21. In this manner the elasticity of the panel is available to the maximum and there is no danger of tearing the cuff or sleeve or of breaking the stitches securing the same together during use. This is an important feature in that it enhances the effi-

ciency of the invention and renders it durable and of an attractive appearance.

While the elastic means has been illustrated as a trapezoidal panel or insert of "Lastex" secured by stitches, it may of course take other coplanar forms, sizes and shapes, as will be apparent to one skilled in the art; for example, the entire cuff may be elastic material, such as "Lastex", or the cuff fabric may include a sufficient number of elastic threads. Referring to Figure 1, where the cuff of this invention is shown applied to the wrists of a wearer, the elastic means in the cuff provides a gentle but sufficiently snug binding fit of the cuff to the wrist, so that the sleeve is adjustably retained in relation to the 15 wrist in a manner to prevent the slipping down of the cuff on the wrist, whereby objectionable exposure of the sleeve is avoided in the case of overlength sleeves. Hence, it will be seen, that for a given neckband size it will no longer be 20 necessary to manufacture seven distinct sleeve lengths, for example, 31 to 37 inclusive, as graphically shown in Figure 3, as is current practice in the case of white shirts, which is the case illustrated. On the contrary, it is sufficient to provide two sleeve lengths only, namely, 33 and 36, shown in full lines in Figure 3, to accommodate in a satisfactory manner all reasonable demands 25 from the standpoint of neatness and comfort. There results therefore a very substantially simplified 30 and saving in the manufacture and merchandising, the importance of which will be readily understood.

In the case of colored or "novelty" shirts it is current practice to make these up in sleeve 35 lengths of 33, 34, 35 and, by the use of this invention, a single sleeve length will actually suffice to meet demands normally requiring sleeve lengths of 32 to 35 inclusive.

In the manufacture of a shirt embodying the present invention, the appropriate size of insert, based upon neckband size of the shirt, is sewed along one edge, preferably, the longest edge to the bottom of the sleeve, by means of loose stitching as explained above. The top of the insert is 45 associated with the previously pleated portion 21 of the sleeve or the pleating is accomplished simultaneously with the forming of the line of stitching 19. Thereafter the insert is stitched to the edges of the portions 17 and 18 of the cuff 50 by lines of stitching 20 or the stitching 19 and 20 may be a continuous or simultaneous operation. The cuff is of course cut so as to receive the trapezoidal insert in the manner shown. Where a two-ply cuff is used the side edges of the 55 "Lastex" are sewed between the plies. As stated, the stitching in all cases is of a type to present a smooth or unobtrusive appearance and the insert is for all practical purposes indistinguishable from the remainder of the cuff, sleeve or shirt. After the sewing operation the cuff is finished in the usual manner.

By the term "coplanar" we mean that the elastic means are within the plane of the cuff, when the cuff is in a flat position.

Various modifications or changes may be resorted to all of which are comprehended within the scope of the appended claims.

We claim:

1. An outer shirt having a sleeve and a cuff 70 portion, the latter being in continuation of the sleeve and exposed, the cuff portion being split and provided with fastening means, said cuff portion provided with elastic means within the 75 confines of the cuff and within the plane thereof for

rendering the sleeve retainable in relation to the wrist, whereby objectionable exposure of the sleeve is avoided.

2. An outer shirt having a sleeve and a cuff portion, the latter being in continuation of the sleeve and exposed, the cuff portion being split and provided with fastening means, said cuff por-

tion consisting substantially entirely of a single continuous layer of elastic material coplanar with said sleeves for rendering the sleeve retainable in relation to the wrist, whereby objectionable exposure of the sleeve is avoided.
